UNITED STATES PATENT OFFICE.

EDWARD F. ROGERS, OF CHELSEA, ASSIGNOR TO HIMSELF, STOUGHTON B. HOLDEN, OF WOBURN, AND LUTHER L. HOLDEN, OF BOSTON, MASS.

IMPROVEMENT IN COMPOSITIONS FOR FIRE-BRICKS.

Specification forming part of Letters Patent No. 119,723, dated October 10, 1871.

To all whom it may concern:

Be it known that I, EDWARD F. ROGERS, of Chelsea, in the county of Suffolk and State of Massachusetts, have invented certain Improvements in Fire-Brick, of which the following is a specification:

The present invention relates to certain new and useful improvements in fire-bricks whereby a lighter, more durable, and less expensive fire-brick than those ordinarily in use, and one that will not clinker, is produced.

My improved fire-brick is composed of the following materials, compounded in the proportions and in the manner hereinafter described: Of gilders' whiting or magnesia I take two parts, generally using the former on account of its cheapness, together with two parts of plaster of Paris, and one part of black lead or lamp-black, and mix the above ingredients with a solution of soda water made from common washing soda or any kindred solution. I then work up the above mixture in the method adopted in making brick from clay. The compound is then left to dry in a warm atmosphere—not in the sun—say of six-

ty degrees, for thirty hours, and then baked in an oven, and is generally formed in pieces of one inch in thickness.

By the process above-described a fire-brick is made which can be cut and used the same as and in place of soap-stone, is lighter in weight, more durable, cheaper per pound than, and will not clinker, like ordinary fire-brick, and is easily transported, and can be used in thin pieces for stoves, ranges, furnaces, &c.

Having thus described my improvements, what I claim as my invention, and desire to have secured to me by Letters Patent, is—

Fire-bricks composed substantially of the several ingredients specified herein, and in the manner substantially as described.

In testimony whereof I have signed my name to this specification in the presence of two subscribing witnesses.

EDWARD F. ROGERS.
